FLUID PUMP

Walter H. Hermsdorf and Allan W. Aroner, Chicago, Ill., assignors to S. H. G. Incorporated, Chicago, Ill., a corporation of Delaware

Application December 8, 1933, Serial No. 701,442

1 Claim. (Cl. 103—132)

This invention relates to improvements in fluid pumps and refers particularly to a fluid pump of the rotary type having a plurality of pistons so eccentrically disposed upon the pump shaft as to dynamically balance the shaft and permit of the employment of relatively high pump speeds.

The object and advantages of our invention will be apparent from the accompanying drawings and detail description.

10 In the drawings, Fig. 1 is a transverse sectional view taken on line 1—1 of Fig. 3 illustrating an embodiment of our invention.

Fig. 2 is a sectional view taken on line 2—2 of Fig. 1.

15 Fig. 3 is a sectional view taken on line 3—3 of Fig. 1.

Fig. 4 is a sectional view taken on line 4—4 of Fig. 1.

20 Fig. 5 is a fragmentary sectional view illustrating particularly the inlet and discharge ports of one of the cylinders.

Fig. 6 is a fragmentary sectional view, illustrating a slightly modified port construction.

Fig. 7 is a top plan view of the portion of the 25 device shown in Fig. 6.

Fig. 8 is a fragmentary detail elevation, parts being broken away and parts being shown in section, of another modified form of port construction.

30 Fig. 9 is a top plan view of the portion of the device shown in Fig. 8.

Referring in detail to the drawings, 1 and 2 indicate drums or cylinder walls closed at opposite ends by heads 3 and 4 and separated by 35 an internal partition 5. Drums 1 and 2, heads 3 and 4 and partition 5, is assembled as a unitary structure, being secured together by bolts 6 which pass through members 1, 2, 3, 4 and 5. The body thus formed is divided into two compartments or cylinders 1 and 2.

40 Bosses 9 and 10 may be formed on heads 3 and 4 respectively, said bosses being hollow and adapted to carry bearings 11 and 12 respectively. A shaft 13 may be journaled in bearings 11 and 45 12, and may pass through cylinders 1 and 2, said shaft being coaxially disposed with respect to the walls 1 and 2. The opening in boss 10 may be closed at the end by plug 14 and a packing gland and nut 15 adapted to confine packing 50 material 16, may serve to prevent leakage of fluid or oil along shaft 13 at its opposite end.

55 Eccentrics 17 and 18 may be positioned upon shaft 13 within cylinder 1 and 2 respectively, said eccentrics being locked upon the shaft by means of keys 19 which may be maintained in place by

set screws 20, one only of which is shown in the drawings. In the embodiment shown, the eccentrics 17 and 18 are displaced 180° apart, one piston being adapted to counterbalance the other when shaft 13 is rotated, as will be hereinafter 5 more fully described. However, if desired, two or more cylinders and eccentrics may be used so long as the angular displacement of the eccentrics is uniform. For instance, if three are used, the displacement may be 120°; if four are 10 used, the displacement will be 90° and so on in equal multiples of 360°.

Eccentrics 17 and 18 may be circular in section and may be adapted to carry pistons 21 and 22 respectively, said pistons being adapted to ride 15 upon the circular periphery of the eccentrics. The throw of the eccentrics, that is, the distance between the center line of shaft 13 and the axes of eccentrics 17 and 18 is such, taken in conjunction with the radii of pistons 21 and 22 20 which are circular in section, as to permit the periphery of the pistons, when shaft 13 is rotated, to osculate or be brought into a tangential relationship with the inner walls of the cylinders.

Above each of the cylinders 1 and 2, drums 1 25 and 2 may be provided with transverse bores 23 and 24, said bores being in communication with each other and with the upper portion of the cylinders. A vane 25 may be positioned at one end in a slot provided in the upper portion of 30 each of the pistons 21 and 22, said vanes being rigidly secured within said slots by means of pins 26. The opposite portions of vanes 25 may extend upwardly into bores 23 and 24. Half-round members 27 may be positioned within 35 each bore 24, each vane 25 extending between said members. The construction is such that when shaft 13 is rotated, pistons 21 and 22 are prevented from rotating by means of vanes 25. However, by the provision of the half-round 40 members 27 which form a knuckle joint and by means of the slidable relationship between vane 25 and half-round members 27, pistons 21 and 22 are permitted to move in an orbital fashion 45 within said cylinders, a portion of each of the pistons being in sliding contact with the walls of the respective cylinder.

The upper portions of drums 1 and 2 may be provided with bores 28 and 29 respectively, said bores communicating at one end with cylinders 1 50 and 2 respectively, the opposite ends of said bores opening into compartment 30 formed by the hollow cap 31 which may be mounted on the upper portion of said drums by means of machine screws 32 or the like. Cap 31 may be provided 55

with a boss 33 in which an aperture 34 is formed and through which fluid may be drawn into the cylinders.

The upper portion of drum 2 may be provided with a bore 35 which may extend transversely through the thickness of said drum. Head 4 may be provided with an opening 36 as may also partition 5, openings 36 in said head and partition forming a continuation of bore 35. Drum 1 may be provided with recess 37 which may be in communication with opening 36 in partition 5. Conduits 38 and 39 may be respectively provided in drums 1 and 2, said conduits respectively connecting into recess 37 and bore 35, permitting communication between cylinders 7 and 8 and outlet pipe 40 which may connect into opening 36 provided in head 4.

It is to be observed that bores 28 and 29 which serve as the intake for cylinders 7 and 8, and conduits 38 and 39 which serve as discharge ports or exhausts for said cylinders, are positioned on opposite sides of vanes 25. The construction of vanes 25 and knuckle joints 27 is such as to prevent direct communication between the inlet and outlet of the cylinders. Consequently, it can readily be seen that communication between the inlet and outlet of each cylinder must take place through the medium of the orbital travel of each piston.

In operation, shaft 3 may be driven by any suitable prime mover, not shown. Assume for the sake of illustration that shaft 13 is driven in a counterclockwise direction as viewed in Fig. 1. As has been hereinbefore described, eccentricities 17 and 18 are displaced 180° away from each other. Consequently, in the phase of operation shown in Fig. 1, piston 21 is at the upper portion of its orbital path whereas piston 22 is at the diametrically opposite position. In the period of operation illustrated, piston 22 is moving in a counterclockwise orbital path and is forcing air through outlet 39. Simultaneously air is being drawn by said piston through inlet 29. Piston 21 has just completed its cycle and is about to open discharge port 38 and close inlet 28. As said piston continues its counterclockwise orbital movement, the air previously drawn into cylinder 7 and confined within that space constituting the difference in volume between piston 21 and cylinder 7, will be compressed and will be forced through outlet 38 into discharge pipe 40.

It can readily be seen that even though pistons 21 and 22 are eccentrically mounted upon shaft 13, the uniform angular displacement of said eccentricities is such as to produce a dynamic balance. Consequently, shaft 13 may be driven at relatively high angular velocities without producing an excessive amount of vibration. In addition, by the provision of a plural number of cylinders, the pressure of the air delivered is more or less uniform throughout the cycle of operation depending, of course, upon the number of cylinders used.

A pipe 41 may be threaded to boss 10 and may communicate with conduit 42 provided in said boss, said conduit also passing through bearing 12. An annular groove 43 may be provided in shaft 13 and a transverse bore 44 may connect said groove to a longitudinal bore 45 provided in said shaft. A transverse bore 46 may connect longitudinal bore 45 to that portion of shaft 13 upon which eccentric 18 is mounted. Transverse bore 47 may in like manner connect longitudinal bore 45 to that portion of shaft 13 upon which eccentric 17 is mounted. Bore 48 in similar man-

ner may connect longitudinal bore 45 with that portion of shaft 13 carried in bearing 11. Pipe 41 at its opposite end may be connected to a source of lubricating oil or grease under pressure, not shown, and as can readily be seen, said lubricant may be forced into longitudinal bore 45, from whence it may be delivered to bores 46, 47 and 48 which in turn permit the passage of the lubricant to the various moving parts of the pump. It can readily be seen that shaft 13 at one end is positively sealed by plug 14 whereas packing 16 prevents leakage of lubricant along the opposite portion of shaft 13.

By means of the dynamic balance secured by our invention and the more or less constant load carried by the prime mover, said pump may be directly connected to, for instance, a relatively high speed electric motor and will perform with a maximum efficiency. Heads 3 and 4 may be provided with integral lugs 49 and 50 which extend beneath the lower portion of drums 1 and 2, legs or standards 51 and 52 may be secured to lugs 49 and 50 by means of screws 53, whereby said pump may be mounted upon the same frame that supports the prime mover.

It can readily be seen that a pump constructed in accordance with the concepts of our invention can be used to pump fluids of substantially all types, the same being ideally adapted for pumping or compressing air, or other compressible gases or pumping incompressible liquids.

Referring particularly to Figs. 6 and 7, a slightly modified form of port construction is shown, wherein 1' and 2' indicate the drums comprising the casing of the pump. The upper portion of said drums may carry a boss 3' which may be formed integral with said drums. Said bosses may be provided with a plurality of bores 5', which may connect at their lower ends with counterbores 6' which, in turn, may be in communication with the interior of said drums. A piston 7', identical in construction to pistons 21 and 22 may be positioned within each of the drums 1' and 2', said pistons being mounted and being operable within the drums in a manner identical with pistons 21 and 22.

A transverse bore 8' may be provided in the upper portion of drums 1' and 2', said bore being closed at one end and connecting with an exhaust outlet (not shown) at the opposite end. Another bore 9' may be provided immediately beneath and parallel to bore 8', said bores being in communication with each other. A pair of semi-cylindrical members 10' and 11' may be positioned in bore 9' above each of the drums 1' and 2', each pair being independent and operating separately. A vane 12' may be carried in a slot 13' provided in each of the pistons 7', said vanes being secured in said slots by means of pins 14'. The upper portions of each of said vanes 12' may extend into bore 9', each vane being slidably positioned between each pair of semi-cylindrical members 10' and 11'. The upper ends of vanes 9' extend into bore 8'. Each vane 9' may be provided with a plurality of bores 15' which may be in communication at their upper ends with bore 8'. The lower ends of bores 15' may connect with openings 16' which may serve to establish communication between bores 15' and the interior of each of the drums 1' and 2'.

In operation, each of the pistons 7' may travel in an orbital manner within drums 1' and 2' similar to the travel of pistons 21 and 22. If the pistons 7' are driven in a counterclockwise direction, as viewed in Fig. 6, fluid will be drawn into the

drums through bores 5' and 6' and will be compressed by said pistons and subsequently discharged through openings 16' and bores 15' into bore 8' and from thence to the point of use.

- 5 Referring particularly to Figs. 8 and 9, another modified form of port construction is shown, wherein 1" and 2" indicate the drums comprising the casing of the pump. The pump may, in general, be similar to that shown in Figs. 1 and 3.
- 10 Each of the drums 1" and 2" may be closed by heads 3", one only of which is shown, both of said heads being similar in construction. A boss 4" may be formed on each of said heads and may be provided with opening 5" which may communicate with the interior of the drums. A piston 6" may be positioned within each of the drums 1" and 2", said pistons being mounted and being operated similar to pistons 21 and 22. Each piston 6" may be provided with a bore 7" which may extend transversely across said pistons, said bores being normally closed at each end by heads 3" and a division wall 8" which separate drums 1" and 2". A plurality of bores 9" may connect the exterior of each piston and each bore 7".
- 15 25 The arrangement is such that as pistons 6" travel in their orbital paths, at one period of travel, one end of each of the bores 7" comes into communication with openings 5", thereby inducing fluid through openings 5" into the respective drums. The discharge arrangement is similar to

that shown in Figs. 6 and 7 and is indicated as such by single-primed reference numerals.

It is to be understood that the features of the constructions shown may be utilized in single chamber pumps having single pistons, in which case the pump shaft may be dynamically balanced by means of a separate counterweight.

We claim as our invention:

A pump for fluids comprising in combination, a hollow casing having a cylindrical interior, walls 10 at the ends of said casing, one of said walls being provided with an opening, a piston eccentrically positioned in said casing and movable in a planetary manner therein, a hollow vane mounted upon said piston, said vane being movably associated 15 with said casing to prevent rotation of said piston, the hollow interior of the vane being in communication with the interior of the casing during a portion of the movement of the piston, said casing being provided with an outlet opening in 20 communication with the hollow interior of the vane, said piston being provided with an aperture which during a portion of the movement of the piston is in direct registration with the opening in the casing wall, said piston also being provided with a communication between the aperture provided therein and the interior of the casing.

WALTER H. HERMSDORF.

ALLAN W. ARONER.
